WITNESS:

BY Victor J. Evans

ATTORNEY

UNITED STATES PATENT OFFICE

CHARLES D. DANIELS, OF MOUNTAIN AIR, NEW MEXICO

PLIERS

Application filed July 16, 1927. Serial No. 206,272.

My invention relates to pliers and its principal object is to provide a pair of pliers which are self adjusting and may be opened to a maximum degree.

5 A further object of the invention is to provide a pair of pliers which will hold an object with equal grip when engaged with a small or large object.

10 Still another object of the invention is to provide a pair of pliers which are positive in operation and when engaged with an object will firmly engage the same due to the novel leverage between the plier handles and jaws.

15 With the preceding and other objects and advantages in mind, the invention consists in the novel combination of elements, construction and arrangement of parts and operation, to be hereinafter specifically referred to, claimed and illustrated in the accompanying drawings, wherein:

Figure 1 is a perspective of a pair of pliers constructed in accordance with my invention.

20 Figure 2 is a perspective of the pliers in an opened position.

Figure 3 is a perspective of one of the units of the invention.

Figure 4 is a perspective of the pivoted jaw embodied in the invention.

25 Referring to the drawings in detail, wherein corresponding characters of reference denote corresponding parts throughout the several views, the numeral 5 designates a plier handle having a forwardly extending offset jaw 6 at one end, and a relatively wide intermediate part 5' having its upper face recessed as at 7'.

Arranged in opposed relation to the jaw 6 and cooperating therewith is a pivoted jaw 8 having its underface cut away as indicated 30 at 9 to provide an ear 10 which is received in the recess 7 and is pivoted to the handle 5 by a pivot pin 11.

A movable handle 12 is arranged in opposed relation to the handle 5 and has its

inner face cut away to provide an extension 13 which crosses the jaw 6 and is pivotally connected thereto by a transverse pivot 7. The inner end of this extension 13 extends parallel along the adjacent face of the jaw 8 and is provided with a longitudinal slot 16 which receives a pin or stud 17 carried by jaw 8. Extending from the longitudinal edge of the pivoted jaw 8 at a point adjacent its pivoted end is a lateral extension 17' which is movable in the recessed face of the part 5'. The extension 17' is for the purpose of providing additional bearing surface between the jaw 8 and the handles 5 and 12. In addition, this extension 17' serves to bridge the inner ends of the jaws when the latter are extended, so that small articles will not become wedged between the jaws and prevent their closing movement.

From the disclosure it will be apparent that upon separation of the handles 5 and 12, the pivoted jaw 8 will be moved away from the jaw 6 due to the slotted connection of the extension 13 and the jaw 8.

It will be further noted that when the jaws are in open or closed position they will be retained in such position until they are further moved with respect to each other by operating the handles 5 and 12.

While I have shown and described the preferred embodiment of the invention, it should be understood that changes in the construction and arrangement of parts may be made, and that I am only limited by the appended claim.

80 What is claimed is:—

A tool comprising a handle having an offset rigid jaw at one end, a relatively movable jaw having its inner end pivotally secured to the handle adjacent the inner end of the rigid jaw, an arm extending laterally from the inner end of the pivotally movable jaw and adapted to overlap the handle at a point adjacent the rigid jaw, a second handle pivotally secured to the first mentioned handle for

wardly of the pivotal point of the pivotally movable jaw, a slotted extension carried by said second handle, said extension overlapping the pivoted jaw and projecting beyond the point of pivotal connection with the fixed jaw, and a pivot stud carried by the pivoted jaw beyond the pivot point of the latter and extending into the slot of the handle extension.

10 In testimony whereof I affix my signature.
CHARLES D. DANIELS.
